US0D1044291S

(12) **United States Design Patent** (10) **Patent No.:** **US D1,044,291 S**
(45) **Date of Patent:** **** Oct. 1, 2024**

(54) **PAPER PRODUCT**

- (71) Applicant: **Clearwater Paper Tissue, LLC**,
Spokane, WA (US)
- (72) Inventor: **Henry John Peters**, Shelby, NC (US)
- (73) Assignee: **Clearwater Paper Tissue, LLC**,
Spokane, WA (US)
- (**) Term: **15 Years**
- (21) Appl. No.: **29/755,960**
- (22) Filed: **Oct. 23, 2020**

Related U.S. Application Data

- (62) Division of application No. 29/714,846, filed on Nov. 26, 2019, now Pat. No. Des. 902,605, which is a division of application No. 29/637,903, filed on Feb. 22, 2018, now Pat. No. Des. 871,777.
- (51) **LOC (14) Cl.** **05-06**

(57) **CLAIM**

The ornamental design for a paper product, as shown and described.

DESCRIPTION

The sole FIGURE is a plan view of a paper product. The broken line surrounding the FIGURE depicts the boundaries of the claim and forms no part thereof. The broken lines within the boundary depict portions of the paper product that form no part of the claimed design.

1 Claim, 1 Drawing Sheet
